CLAIM

The ornamental design for a computer, as shown and described.

DESCRIPTION

FIG. 1 is a perspective view showing the front and right side of our new design for a computer according to the present design;

FIG. 2 is a top plan view of the computer of FIG. 1; FIG. 3 is a right side elevation of the computer of FIG. 1; FIG. 4 is a left side elevation of the computer of FIG. 1; FIG. 5 is a front elevation of the computer of FIG. 1; and, FIG. 6 is a rear elevation of the computer of FIG. 1. The broken lines of the computer are for illustrative purposes only and form no part of the claimed design.
